CLAIM

The ornamental design for an accessory for a mobile electronic device, as shown and described.

DESCRIPTION

FIG. 1 is a top isometric view of an accessory for a mobile electronic device showing our new design;

FIG. 2 is a bottom isometric view thereof;

FIG. 3 is a right view thereof;

FIG. 4 is a left view thereof;

FIG. 5 is a front view thereof;

FIG. 6 is a back view thereof;

FIG. 7 is a top view thereof; and,

FIG. 8 is a bottom view thereof.

The broken lines in the drawings depict environmental subject matter only and form no part of the claimed design.

1 Claim, 5 Drawing Sheets
